UNITED STATES PATENT OFFICE.

OTTO H. DE LAPOTTERIE, OF KENT, OHIO, ASSIGNOR TO TOWNSEND COMPANY, OF NEW BRIGHTON, PENNSYLVANIA, A CORPORATION OF PENNSYLVANIA.

METHOD AND APPARATUS FOR FORMING HEADED ARTICLES.

1,417,806.

Specification of Letters Patent. Patented May 30, 1922.

Application filed March 1, 1918, Serial No. 219,841. Renewed April 8, 1921. Serial No. 459,716.

To all whom it may concern:

Be it known that I, OTTO H. DE LAPOTTERIE, a citizen of the United States, residing at Kent, in the county of Portage and State 5 of Ohio, have invented certain new and useful Improvements in Methods and Apparatus for Forming Headed Articles, of which the following is a specification.

My invention relates to a method and ap-

10 paratus for forming rivets, nails, bolts or other articles which are made from metal stock, such as a bar or rod, by forging, upsetting or other like operations involving the flow of metal.

15 My invention particularly comprises the application of electrical heating to the metal stock while in the machine and the addition of electrical heating apparatus to machines for manufacturing articles of the kind de-

20 scribed.

My invention further relates to a method and apparatus for forming rivets and the like, and has for its principal object to produce an improved rivet in which that portion only of the blank which forms the rivet head has been heated to a temperature high enough to facilitate upsetting of the head.

25 My improvements may be applied, for example, to heading machines of the kind now commonly used for hot or cold rivet making. Such machines usually comprise means for feeding a long length of metal stock, a rod or bar into the machine, means for shearing off a blank and means for heading the blank to form the desired article; and are usually automatic or semi-automatic in operation.

30 My invention comprises the addition to such machines of means for heating the metal which is to form the rivet or like article while it is in the machine and preferably during the process of shearing the rivet blank from the stock-bar or rod.

35 The heating is preferably performed by subjecting the rod or bar or only a portion thereof to electrically produced heat, the rod, bar or other metal stock itself forming part of an electric circuit. The electrical apparatus may be of any well known type capable 50 of furnishing a current of high amperage at low voltage.

A specific example of my invention is hereinafter described as it has been applied

to a machine for making headed nails or rivets.

55 That portion of such a heading machine in which my invention is incorporated is shown in the accompanying drawings, in which—

Figure 1 is a vertical sectional elevation;

Fig. 2 is an end view of Fig. 1;

Fig. 3 is a plan of Fig. 1;

Fig. 4 shows the position of the parts with the gripping dies open;

Fig. 5 shows the position of the dies when 65 the blank has been partially sheared off;

Fig. 6 shows the gripping position of the dies with the sheared off blank ready to be headed;

Fig. 7 shows a usual type of cold-formed 70 rivet;

Fig. 8 shows a rivet formed by the present invention;

Fig. 9 shows a rivet of the shape produced by hot-forming.

75 In Fig. 1, A is the bed plate of the machine in which are mounted the usual fixed die block D carrying one gripping die N and the movable or reciprocating die block S carrying the other gripping die E. The means for moving or reciprocating the die block S are not shown as they are well known in the art and form no part of my invention.

K is the stock-bar or rod from which the rivet blanks are cut off and is preferably of 85 cold-drawn steel. This rod is fed forward either by hand or preferably by automatically actuated rolls B—B, the lower roll being mounted on and actuated through shaft C, the shaft of the upper roll being 90 mounted in the housing I.

F is a back plate carrying the cutting off die O which is insulated from the back plate and bed plate by insulation O'. J is a feed tube surrounded by an insulating tube J' 95 mounted in an opening in the bed plate, its inner end registering with the central opening in the die O. H is the heading tool mounted on a header-slide G and actuated in the usual manner.

100 Current is delivered to the machine from any suitable source, such as a dynamo 1 and transformer 2, one side of the circuit being connected to conductor R, shown as clamped to the bed plate by an insulated bolt M. This conductor R is connected to a brush

or brushes Q bearing against the lower feed-roll B, this roll being insulated from the shaft C but mechanically connected thereto by an insulated key L. Any other means 5 for insulating the rolls may be used.

The other side of the circuit is connected by conductor R' and bolt M' to the stationary die block D, both die blocks and dies and the bed plate being thus electrically connected. 10

In practice a low voltage is used, but the circuit is so designed as to carry a current of large amperage.

It will thus be apparent that the stock-bar 15 or rod K when fed through the feed pipe J and die O is electrically insulated from the rest of the machine until it is brought into contact with the movable die.

W is a friction disk or brake arranged to 20 prevent any backward movement of the feed roll so that the end of the stock-bar or rod in the machine is held in contact with the surface of the moving die block for a purpose herinafter stated.

25 The operation of the machine is as follows:—The bar or rod to be headed is fed by the feed rolls through the tube J and die O until a length sufficient to form a rivet or the like extends beyond the die. The extent to 30 which the rod projects may be controlled in the usual way by a stock-gauge.

The movable die E then travels across the face of die O and shears off the blank. As 35 soon as die E comes into contact with the rod K, electrical connection is made and current flows through the rod and tends to heat the same. As the cross section of the bar is gradually diminished by the action of the die, the electrical resistance of the bar at this portion 40 increases with a consequently large localized development of heat, which in practice has been found to be sufficient to cause that portion of the end of the rod within the die O to be raised to the desired temperature. As the 45 protruding portion of the rod is in contact with the massive die, its temperature is not raised to any material extent, but that portion of the rod K within the die O is rapidly raised to the temperature desired, and by

50 proper adjustment of the conditions as to time of operation and quantity of current, this heated portion may be made to extend only through that part of the rod which is later to be made into the head of the rivet.

55 The movable die, in its further movement, completely shears off the blank and grips it against the stationary die, whereupon the heading tool advances and heads the rivet. The movable die then moves back to its original 60 position and the operation is repeated. During the back and forth movement of the movable die, it moves across the end of the sheared rod with which it makes a more or less imperfect electrical contact, the passage 65 of the current through this relatively high

resistance connection causing a further localized heating of the end portion of the rod which continues as long as the movable die is in contact with the rod.

At each succeeding operation, therefore, a 70 blank with a heated head portion is brought into position opposite the heading tool which forms the head into any of the desired shapes which can be made by hot riveting, while the shank remains substantially cold. 75

The finished rivets are ejected from the dies by an automatic kick-out or in any of the other well known ways.

The improved rivet made by my machine has an accurately gauged shank with a 80 squarely cut off end, and can have any desired form of head, for example, that shown in Fig. 8, which could not be made cold, the shape shown in Fig. 7 being the best that can be done by the cold rivet making process. 85

A hot-formed rivet can be made with a pointed head, as shown in Fig. 9, but its shank is liable to be distorted from a true cylindrical shape, and the shearing is liable to produce an irregular and inclined end instead of one at right angles to the axis of the shank. The irregularities in the ends of hot formed rivets cause difficulty when the rivets are set in plates having chamfered openings, since the openings are not uniformly filled 95 flush with the surface of the plate and the superfluous metal must be chipped off. My new form of rivet obviates this difficulty. 90

In actual operation, I have found that the end portion of the blank can be electrically 100 heated by the means described to such a temperature that it will readily flow under the action of the heading tool. The heating of the end portion of the rod, which is later to form the head portion of the rivet, moreover, 105 can be so localized that the adjacent portion of the rod which later forms the shank of the rivet remains practically unheated, this condition being maintained during the shearing operation because of the close physical 110 contact of this shank portion of the blank with the massive die, the previously heated end portion of the blank extending beyond said die.

My invention is applicable not only to 115 rivets, but to nails, bolts or other headed articles of iron, steel, copper, bronze or other metals; and while I have shown my invention as applied to one form of heading machine it is obviously applicable to other 120 forms of machines and is further not to be limited to the particular details of construction shown.

Obviously also the machine may be used 125 to heat more than the head-forming portion of the stock-bar or rod, so that the articles are formed by the usual hot-forming process. This result can be obtained by proper variation of the factors of time and quantity of current. If the machine is 130

slowed down so that the stock-bar or rod is subjected to the heating action of the current for a longer time, or if a larger current is used, any desired extent of the bar or rod 5 may be heated to any predetermined temperature.

The invention is also obviously applicable to the formation of articles from any kind 10 of metal stock, whether continuous or not, as long as it is in such shape, form or condition as will permit of its being fed into, and electrically heated to a working temperature, in machines by which it is manufactured into formed articles.

15 I believe that I am the first to make, by machinery, an article formed as an entirety from stock electrically heated within a machine to a temperature at which the solid metal will flow and in which machine the heated metal is shaped by pressure to form 20 the article.

I claim:

25 1. In a heading machine, the combination of means for feeding a rod or bar, means for shearing a blank therefrom comprising a movable die, and means for passing an electric current through said rod or bar and said die.

30 2. In a heading machine, the combination of a bed plate, a cut off die insulated therefrom, insulated means for feeding a rod or bar to said die, a movable die, and means for delivering electric energy to said feeding means and movable die, whereby the rod is 35 included in an electric circuit.

35 3. In a heading machine, the combination with means for feeding a rod or bar, of means for shearing off a portion of said rod, and means for electrically heating said rod 40 during the shearing operation.

40 4. In a heading machine, the combination with a cutting-off die, a movable die arranged to cooperate with said cutting-off die to shear off a blank, means for feeding

a rod or bar through said cutting-off die, 45 and means for electrically heating the end portion of said rod within said cutting-off die, said movable die being arranged to engage the unheated portion of said blank.

5. In a heading machine, the combination 50 of heading mechanism, a stationary clamping die, a movable clamping die, means for electrically heating the end portion of a blank, and means for feeding said heated blank to said clamping dies. 55

6. In a heading machine, the combination 60 of heading mechanism, a stationary clamping die, a movable clamping die, means for electrically heating a blank, and means for feeding said heated blank to said clamping dies.

7. In a heading machine, the combination 65 of a cutting-off die, means for feeding a rod or bar therethrough, means for electrically heating a portion of said rod or bar, a movable die arranged to shear off a blank from said rod, a stationary die arranged to cooperate with said movable die to hold the blank, and a heading device.

8. The method of making headed metal 70 articles, which consists in electrically heating a portion only of the metal from which the article is to be formed by causing sufficient current to pass through said metal and gradually diminishing the cross section of 75 the metal during the passage of the current, and thereafter forming the article from said heated portion.

9. The method of making headed metal 80 articles, which consists in electrically heating the metal from which the article is to be formed by causing sufficient current to pass through said metal and gradually diminishing the cross section of the metal during the passage of the current, and thereafter forming the article from said heated portion. 85

In testimony whereof, I affix my signature.

OTTO H. DE LAPOTTERIE.
